UNITED STATES PATENT OFFICE.

THEODORE G. CRANE, OF CHICAGO, ILLINOIS, ASSIGNOR TO AIROBLAST CORPORATION,
A CORPORATION OF NEW YORK.

APPARATUS FOR SMOKING AND CURING MEAT.

1,414,504.

Specification of Letters Patent.

Patented May 2, 1922.

Application filed December 17, 1920. Serial No. 431,418.

To all whom it may concern:

Be it known that I, THEODORE G. CRANE, a citizen of the United States, and a resident of the city of Chicago, in the county 5 of Cook and State of Illinois, have invented certain new and useful Improvements in an Apparatus for Smoking and Curing Meat; and I do hereby declare that the following is a full, clear, and exact description of the 10 same, reference being had to the accompanying drawings, and to the numerals of reference marked thereon, which form a part of this specification.

My invention relates particularly to an 15 apparatus used in smoking meat and the like and is an improvement over the apparatus illustrated in the patent to Schwenger No. 1,133,888. The Schwenger device has not proved satisfactory since the blast of 20 air was directed at the top of the sawdust or whatever smoke producing material was used. This would create a thick cover over the sawdust or cake the same and greatly interfere and obstruct the action of the 25 smoldering combustion that produces the smoke, and prevent the combustion from sufficiently penetrating the smoke producing material. My invention, among other things, is designed to overcome this defect.

30 It is therefore an object of this invention to provide an apparatus that causes proper combustion of the smoke producing material.

It is also an object of this invention to 35 provide an apparatus that properly aerates the smoke producing material.

It is also an object of this invention to provide means for producing an even temperature.

40 It is a further object of the invention to provide an apparatus that can be easily controlled.

Other and further important objects of 45 this invention will be apparent from the disclosures in the specification and drawings.

The invention (in a preferred form) is illustrated in the drawings and hereinafter more fully described.

On the drawings:

50 Figure 1 is a perspective view of my apparatus as installed for service.

Figure 2 is substantially a bottom plan view of a smoke house showing a portion of my apparatus in top plan view.

Figure 3 is a side elevation of the apparatus shown in Figure 2.

Figure 4 is a section on the line 4—4 of Figure 3.

Figure 5 is a section on the line 5—5 of Figure 3.

Figure 6 is a sectional detail of a jet used for heating purposes, taken on the line 6—6 of Figure 7.

Figure 7 is a top plan view thereof.

Figure 8 is a section through the air blast pipe.

Figure 9 is a section through the main air pipe showing a valve mechanism.

Figure 10 is a section at the juncture of the gas and air pipes.

As shown on the drawings:

In the different figures of the drawing, similar features are denoted by similar reference numerals.

Briefly described, my apparatus comprises primarily a system for aerating and igniting a mass of smoke producing material such as sawdust, preferably from within the mass or interiorly thereof, for creating the smoke necessary for smoking and curing meat. And as the area or size of smoke houses vary, it is contemplated that my apparatus may be made in units so as to serve different sizes of smoke houses. According to my apparatus or system a unit comprises 75

a single air blast and ignition pipe closed at its free end, buried in a mass of sawdust or the like and means for heating the same to ignite the sawdust and passing air therethrough to aerate the sawdust. A two unit 80 system comprises two air blast and ignition pipes, closed at their free ends and buried in a mass of sawdust of greater area and means for heating the same for igniting the sawdust, and for forcing air therethrough. 85 Thus by increasing and decreasing the units, my apparatus or system can be adapted for 90 various sized smoke houses.

In the present embodiment of my invention I have illustrated in Figure 1 a two 100 unit system. One unit comprises the perforated air blast and ignition pipe or element 1 having its end closed, shown as covered by or buried in sawdust, and the heated and heat conducting and air supplying pipe 2. The other unit comprises the perforated air blast and ignition pipe or element 4 having its end closed, covered 105

with sawdust, and the heat conducting and air supplying pipe 5. For the purpose of heating these pipes a gas jet pipe 3 is supported underneath the same on brackets 6 which in turn are supported by vertical brackets 8 which also support brackets 9 in which the heat and air supply pipes are mounted. Any number of these brackets and supports may be used depending upon 10 the length of the units. These supports are designed with upper inclined flanges or slopes to support a reverberatory hood or heat deflector 10, so that the heat rising from the gas flames from said pipe 3 will 15 be subsequently directed downwardly thereby. The ignition pipes 1 and 4 are also preferably arranged in parallel relation with the pipes 3 and substantially co-extensive therewith and are respectively connected to the rear end thereof by angled 20 swivel joint couplings 11 and short pipe sections 12, the pipe sections 12 fitting in the angled swivel couplings 11 and also in angled couplings 13 on the ignition pipes 25 1 and 4, as clearly shown in Fig. 2. The perforations 15 in the ignition pipes 1 and 4 may be staggered therearound to properly aerate the sawdust, but I preferably put them in the bottom of the pipes so that the 30 gusts of air will be deflected from the floor and be scattered in different directions. For this purpose the pipes 1 and 4 should be supported a short distance from the floor, and as they can be easily swung upwardly on the swivels 11, it is a simple matter to so support them, and if desirable the 35 pipes may be supplied with the collars 14 to properly space them from the floor.

The gas jet pipe 3 that heats the pipes 40 2 and 5 is preferably provided with jets at frequent intervals which may consist of thimbles 16 (see Fig. 6) threaded into apertures in the pipes and having toothed or gear like tops 17 for scattering the heat and directing it toward the pipes 2 and 5. Thus the gaseous fuel will enter the pipe 3 and when ignited will heat the heat conducting pipes 2 and 5, through which the air is conducted to the ignition pipes 1 and 4, respectively, and the heat will quickly radiate 50 from the pipes 2 and 5 to the ignition pipes 1 and 4, which will soon become sufficiently hot to ignite the saw dust or whatever smoke producing material is used and the 55 air blasts through the perforations 15 will aid the combustion so that a good volume of smoke is soon attained.

It is contemplated that gaseous fuel be 60 fed to the jet pipes and air to the other pipes during the operation of my system. A convenient method of accomplishing this consists in connecting each gas jet pipe of a unit with a common source of supply and each air supply pipe of a unit with a common source of air supply. When only two

units are used, this can readily be effected by the use of Y pipe coupling 16', and the coupling 17', the branches of the Y coupling fitting over the free open ends of the air pipes, thus the coupling 16' connects the air pipes with an air supply pipe 18 and the coupling 17' connects the gas jet pipe with a gas supply pipe 19.

The forced currents of air are produced by an air pump or blower 20 suitably supported, from which the air is pumped to a main air pipe 21 to which the air supply pipe 18 is coupled, and as it is desirable to mix some air with the gas, I extend the main pipe 21 below its point of connection with the air supply pipe 18 and couple the same with the gas pipe 19. A practical way of effecting this coupling is shown in Fig. 10, which illustrates an air nozzle 22 having a restricted opening secured on the lower end of the main air pipe 21, a coupling 23 being secured to the nozzle, and this coupling is provided with a threaded part for receiving the gas supply pipe 19 and a second threaded part at right angles thereto for receiving the gas pipe 24 which may lead from the city main or other source of supply. Thus a certain amount of air will enter through the nozzle 22 and be mixed with gas entering from the gas pipe 24, the mixture passing on through the gas supply pipe 19 to the jet pipe.

The supply of gas in the gas pipe 24 may be regulated by the valve 25 and the amount of air for mixing purposes with the gas may 100 be regulated by a valve 26 in the pipe 21, and to prevent the gaseous mixture from backing up through the nozzle 22 and pipe 21 into the air pump, a one-way valve is preferably inserted just above the coupling 23. 105 Fig. 9 illustrates one form of valve that may be used, and for the purpose of supporting said valve, a special coupling 27 is used which connects the ends of the air pipe in spaced relation and supports the one-way 110 valve 28 which is pivotally mounted in the coupling at 29 and counterweighted at 30. The valve fits snugly against the bottom of the upper pipe section, but the air can force it open against the resistance of the weight 115 30. But in case the air pump or blower ceases to operate whereby the gas pressure exceeds the air pressure, the valve immediately closes preventing the gas from backing up into the pump or blower. This valve 120 can be made adjustable by screw threading the coupling 27 on the pipe section as is obvious.

The heat of combustion in the smoke house produces the meat curing temperature which 125 should be even throughout the smoke house to get the best results. It frequently happens that the door provides access for some cold air and likewise the space at the walls, especially the wall exposed to a cold north or 130

westerly wind. To provide against such occurrences, I have illustrated the hot air delivery pipes 31 and 32 which are respectively connected with the hot air pipes 5 and 2 and 5 are directed so as to deliver heated air to remote parts of the smoke house that need heating, thus assuring an even temperature throughout.

It is contemplated that the gas jets on the 10 jet pipe 3 may be lighted in any well known manner. Any accessible one can be lighted, the other jets being automatically lighted from this one, one after the other; all the jets on the pipe 3 being sufficiently close so 15 that one will light the adjacent ones as is well known.

In Figure 5 I have shown a series of jets 20 in a transverse plane through the pipe, the lower one of which when ignited will direct the flame thereof to ignite the sawdust from the top. Any number of these sawdust lighting jets may be used if desirable since they aid in the combustion on the surface 25 of the sawdust, and when used in combination with main ignition pipes 1 and 4 produce excellent results.

When it is desired to use my apparatus after the same has been installed in a smoke house or chamber, and the proper amount of 30 sawdust or smoke producing material has been spread over the air blast and ignition pipes 1 and 4, the valves 25 and 26 may be adjusted to admit the gas from the gas pipe and the air from the operating pump or 35 blower 20 which it is contemplated has been put in operation. The main volume of air will enter the air supply pipe 18 and be delivered through the heat supplying pipes 2 and 5 to the ignition pipes 1 and 4, where it 40 will be forced through the apertures 15 and aerate the sawdust. A certain amount of air will be forced through the valve 26 and be mixed with the gas entering from the gas pipe 24. The gaseous fuel will then enter 45 the jet pipe 3 and may be ignited as previously explained to heat the pipes 2 and 5. As iron conducts heat very rapidly, the ignition pipes which are practically a continuation of the air pipes 2 and 5 will be 50 quickly heated to a point where the sawdust will be ignited.

It should be noted that the air that aerates the sawdust interiorly thereof is heated as it passes through the pipes 2 and 5, and this 55 hot air will materially aid the combustion in producing a large volume of smoke and as the combustion begins from a point well within the mass of material, which is feasible on account of the air current passed therethrough, it is obvious that no caking 60 will occur and that the sawdust can be practically all utilized, and during this operation the pipes 31 and 32 will deliver hot air to the cold parts of the smoke chamber, pro-

ducing thereby a very even temperature. 65 When combustion is well under way, the gas may if desirable be greatly decreased or entirely shut off, since the blasts of air directed through will fan the combustion.

It will accordingly be observed that my 70 apparatus is efficient, economical, and productive of the best results, and that it can be made in one or more units to suit the size of the smoke house it is desired to serve.

I am aware that numerous details of construction may be varied through a wide range without departing from the principles of this invention, and I therefore do not purpose limiting the patent granted otherwise than necessitated by the prior art. 75 80

I claim as my invention:

1. A meat smoking apparatus comprising a perforated ignition element adapted to be buried in the smoke producing material, and means for heating said element and 85 passing air therethrough.

2. In a meat smoking apparatus, an ignition element adapted to be placed interiorly of a mass of smoke producing material, and means for heating said element. 90

3. A meat smoking apparatus comprising a perforated ignition pipe adapted to be buried in a mass of smoke producing material, a heat conducting and air supplying pipe coupled thereto, a gas jet pipe for heating said heat and air supplying pipe, and means for supplying gas to said jet pipe and air to said heat and air supplying pipe for the purpose described. 95

4. In a meat smoking apparatus, a combined ignition and air blast element adapted to be buried in a mass of smoke producing material, means for passing air through said element, said air being directed downwardly from said element and subsequently passing 100 upwardly through the smoke producing material, and means for heating said element.

5. An apparatus for curing meat comprising a combined air blast and ignition member adapted to be inserted in a mass of 110 smoke producing material, in combination with means adapted for directing preheated air against the chilled walls of the smoke house.

6. In an apparatus used in curing meat, 115 a heated air blast element adapted to be buried in a mass of smoke producing material, and means adapted for conveying heated air from said air blast element to a remote part of a smoke house. 120

7. In an apparatus used for curing meat, a hollow perforated member adapted to be buried in a mass of smoke producing material, a heat and air conveying pipe connected to said member, and means for heating said 125 pipe and forcing air therethrough.

8. In an apparatus used for curing meat, a support, a pair of pipes mounted on said

support, a second pair of pipes connected to said first mentioned pipes by swivel couplings, said second pair of pipes being perforated and adapted to be covered with a mass of smoke producing material, and means for heating said first mentioned pipes and forcing air therethrough.

In testimony whereof I have hereunto subscribed my name in the presence of two subscribing witnesses.

THEODORE G. CRANE.
